UNITED STATES PATENT OFFICE.

ROBERT H. TODD, OF PHILADELPHIA, PENNSYLVANIA.

RAILWAY-SIGNAL.

1,160,013.

Specification of Letters Patent. Patented Nov. 9, 1915.

Application filed April 22, 1914. Serial No. 833,755.

To all whom it may concern:

Be it known that I, ROBERT H. TODD, a citizen of the United States, residing at Philadelphia, in the county of Philadelphia and State of Pennsylvania, have invented 5 certain new and useful Improvements in Railway-Signals, of which the following is a specification.

This invention relates to new and useful 10 improvements in railway signals, and has for its principal object to provide an automatic signal which will notify the engineer of a train that another train is in the same block.

Another object of the invention is to provide a device by means of which the engineer of the second train will be notified of 15 the fact that the first train has not yet left the block, thus providing a device for automatically keeping the engineers informed 20 of the presence of trains in the same block.

A further object of the invention is to provide a simple and effective device which may be secured to a locomotive of the ordinary 25 type without changing the construction thereof in any way.

A still further object of the invention is to provide a device which may be easily and quickly connected to the track by means 30 of which the signals may be carried for suitable distances.

With these and other objects in view, the invention consists in the novel combination and arrangement of parts which will be 35 fully set forth in the following specification and accompanying drawings, in which,

Figure 1 is a side view of a portion of a locomotive showing this improved device as it would appear when applied thereto, 40 Fig. 2 is an enlarged end view of the invention, Fig. 3 is an enlarged longitudinal sectional view of the invention showing the details in construction, Fig. 4 is a diagrammatic view showing the several circuits 45 when in operation, Fig. 5 is a detail view of a modified form of intermittent contact wheel, Fig. 6 is an enlarged detail view of the wheel mounting for the constant contact wheel, and Fig. 7 is a side view of 50 Fig. 6.

Referring now to the drawings by characters of reference, the numeral 1 designates as an entirety a locomotive of the ordinary type to which the attachment designated 55 generally by the numeral 2, is secured. The usual track, designated by the numeral 3, is

provided and comprises the ordinary rails 4' and ties 5. The attachment above referred to, preferably comprises the tubular member 4 having secured thereto, the 60 fastening plate 5 which is arranged to receive the screws 6 by means of which the device is to be secured to the locomotive. A suitable plunger 7 is slidable in the sleeve 4 and is provided at its lower extremity 65 with a pair of longitudinally extending arms 8 and 9 having apertures formed in their lower extremities which are arranged to receive the pin 10 to hold the intermittent contact wheel rotatably between the 70 arms. A suitable pair of insulating blocks 11 and 12 are secured to opposite sides of the sleeve 4 and are adapted to hold the contact springs 13 and 14 respectively.

A suitable constant contact member designated generally by the numeral 15 is secured to the locomotive in any suitable manner and comprises the L-shaped bar 16 carrying at its lower extremity the bifurcated block 17 which is arranged to receive the 80 constant contact wheel 18, which will be fully described hereinafter. This contact wheel 18 preferably comprises a cylinder of copper or similar conducting material 85 which is provided with the trunnions 19 which are journaled in the arms of the bifurcated portion as clearly shown in Fig. 6. A band of rubber or similar material 20 is secured near each end of the cylinder 90 and is arranged to prevent a short circuit at intersections where another road crosses.

The intermittent contact wheel which is carried by the attachment designated generally by the numeral 2, comprises the disk 21 of fiber or similar insulating material 95 having one portion of its periphery cut away as at 22 and provided with the recesses 23. A suitable aperture 24 is formed centrally of the disk 21 and is arranged to receive the pin 10 by means of which the device is held in place. A suitable strip of copper or similar material 25 is arranged to seat in the recess formed by the cutaway portion 22 and be secured therein by means of screws or rivets passing through the apertures 26 formed therein and into the recesses 23 formed in the bottom wall of the cut-away portion 22.

In the modified form of the intermittent contact wheel illustrated in Fig. 5 the body 110 portion is formed of the metal disk 27 which is cut away as at 28 and provided

with the recesses 29 in which the screw or rivets for securing the fiber strip 30 is arranged to be secured.

In Fig. 2 the wire which completes the 5 circuit is supported upon the nails 32 and is designated by the numeral 31. The nails 32 are driven into the ties and provided with heads 33 which are bent upwardly and into engagement with the wire to hold 10 the same firmly in place.

In Fig. 4 is illustrated diagrammatically 15 the several circuits of the device, and it will be apparent that the contact spring 13 is connected by means of the wire 34 to the battery 35, the opposite terminal of which has connected thereto the wire 36 which is connected to the binding post 37 of the bell 38.

A wire 39 is connected to the binding post 20 37 and the opposite terminal thereof is in electrical contact with the contact wheel 18. The binding post 40 of the bell is connected by means of the wire 41 to the contact spring 14 as clearly illustrated in Fig. 4. Assuming 25 that a train is in a block and the plate 25 of the intermittent contact wheel is contacting with the rail and with the spring 13, it will be apparent that the current will flow from the battery 35 into the wire 36 and 30 thence through the binding post 37 into the wire 39 from whence it will pass into the constant contact wheel 18 and be passed into the line wire 31. Should another train be in the block and the plate 25 of the intermittent contact wheel be in such position as to 35 contact with the spring 14 and the rail 4, it will be seen that the current will be picked up by the wheel 18, passed through the wire 39 into the binding post 37 of the bell on the second mentioned train from whence it will 40 pass through the binding post 40 into the wire 41 and thence back through the plate 25 and rail 4 to the plate 25 of the first mentioned train from whence it will pass 45 through the contact spring 13 and wire 34 back to the battery. It will thus be seen that the bell on the second mentioned train will be rung. In event that the wheels reverse position so that the plate 25 on the second mentioned train engages the spring 13 and the plate 25 on the first mentioned train engages the spring 14, it will be apparent 50 that the bell on the first mentioned train will be rung, thus notifying the engineers of each train of the presence of another in the block. It is to be understood that the wires 55 31 are separated into blocks which may be of suitable length so that as soon as a train passes out of a block another train may pass 60 thereinto without causing the signal to be given.

It will be evident from the foregoing that the invention constructed as illustrated above will effectively notify all trains of the 65 fact that other trains are in the block and

many of the accidents due to the engineer's not seeing the signal or for any reason, he will be notified, since the bell within his cab will ring and thus accidents may be averted.

While in the foregoing there has been 70 shown and described the preferred embodiment of this invention, it is to be understood that such changes may be made in the combination and arrangement of parts as will fall within the spirit and scope of the invention as claimed. 75

Having thus described my invention, I claim:

1. In a device of the character described, a contacting element a contact wheel carried 80 by the contacting element, said contacting wheel being arranged to automatically and alternately cut in and cut out a circuit, springs connected to the contacting wheel, a second contact wheel for continuous contact 85 with a wire, batteries, one of the contacting springs on the first contact element being connected with the batteries, the opposite terminal of the batteries being connected to the other contact element, a bell carried with in the cab of the locomotive, means connecting the bell with the opposite contact spring on the first mentioned contact element, and means connecting the bell with the opposite contact element whereby when current is 90 sent through the wire and the rail, the contact wheel carried by the first contact element will alternately receive and cut out the current through the bell. 95

2. In a device of the character described, 100 the combination with a contact element comprising a sleeve carried by a locomotive, a plunger slidable in the sleeve, the lower end of the plunger being bifurcated, a wheel rotatably mounted in the bifurcated end of 105 the plunger, a spring to normally force the plunger down and hold the wheel in contact with a railroad rail, insulating blocks carried by the sleeve, contact springs carried by the insulating blocks, said springs being insulated from each other and adapted to engage opposite sides of the contact wheel, a contact plate carried by the contact wheel and adapted to form a connection between the rail and one of the springs at one time, and the rail and the opposite spring at the other time, of a wire carried adjacent the railroad rail and connecting with the second contact element, batteries in circuit with one 110 of the contact springs and the second contact element and adapted to send current through the railroad rail and the wire, and a bell connected with the opposite contact spring and the contact element and adapted to receive current sent through the rail and the wire. 115

3. In a device of the character described, a sleeve carried by a locomotive, a plunger 120 slidable on the sleeve, insulating blocks carried by the sleeve, the lower end of the 125

plunger being bifurcated, a wheel rotatably mounted in the bifurcated portion of the plunger, contact springs carried on the insulating blocks and adapted to engage the 5 periphery of the wheel, said wheel being composed of a contact plate and a non-conducting plate, a second contact element, a wire carried by the track, a wheel carried by the second contact element, a local power 10 source carried by the locomotive, a signal carried by the locomotive, means connecting one pole of the power source to one of the

contact springs, means connecting the opposite pole of the power source to the wheel carried by the second contact element, means 15 connecting the remaining contact spring to the signal and means connecting the opposite pole of the signal to the contact element.

In testimony whereof I affix my signature in presence of two witnesses.

ROBERT H. TODD.
